[57] CLAIM

The ornamental design for a workpiece hold-down device, as shown and described.

DESCRIPTION

FIG. 1 is a top isometric view of a workpiece hold-down device showing my new design;
FIG. 2 is a front elevational view thereof;
FIG. 3 is a back elevational view thereof;
FIG. 4 is a side elevational view thereof;
FIG. 5 is a top plan view thereof; and,
FIG. 6 is a bottom plan view thereof.

Fig. 1.

Fig. 3.

Fig. 2.

Fig. 4.

*Fig. 6.**Fig. 5.*

UNITED STATES PATENT AND TRADEMARK OFFICE
CERTIFICATE OF CORRECTION

PATENT NO. : Des. 345,496

DATED : March 29, 1994

INVENTOR(S) : S.A. Erbach

It is certified that error appears in the above-identified patent and that said Letters Patent is hereby corrected as shown below:

Title page, item [56], under References Cited, first reference, insert--
60-232839 11/1985 Japan--.

Signed and Sealed this

Twentieth Day of September, 1994

Attest:

BRUCE LEHMAN
